(57) **CLAIM**

The ornamental design for a CD stand, as shown and described.

DESCRIPTION

FIG. 1 is a perspective view of a CD stand, showing my new design;

FIG. 2 is right elevation thereof;

FIG. 3 is a left elevation thereof;

FIG. 4 is a front elevation thereof;

FIG. 5 is a rear elevation thereof;

FIG. 6 is a top plan view thereof; and,

FIG. 7 is a bottom plan view thereof.

The broken line showing in FIG. 1 is included for the purpose of illustrating environment and forms no part of the claimed design.

1 Claim, 2 Drawing Sheets
